BOX FORMING MACHINE

Walter E. Pope, Port Dickinson, N. Y.

Application October 10, 1936, Serial No. 105,076

5 Claims. (Cl. 93—36)

My invention relates to a box forming machine and particularly to an apparatus for securely fastening the glued end flaps of paper or cardboard boxes in folded position.

5 Heretofore in the art of paper box making the machine utilized for gluing and fastening the glued box ends in position have been equipped in such manner that only boxes of a certain single size are formable upon a given machine.

10 I have provided an apparatus whereby an easily and readily changeable die or template, the same apparatus may be used for securing the glued ends or flaps of boxes of any desired size.

Also in the known type of machines for this 15 purpose, the presser pad has been operable by a mechanical cam arrangement which forces the pad into contact with the fixed die carrying the box and, the travel of the presser pad and the pressure exerted thereby always being uniform regardless of any variation in thickness of the material of which the boxes are made. By my invention I have provided a means whereby an absolutely positive and uniform application of pressure is possible at all times and regardless of the 20 thickness of the material of the box.

In these respects, my invention is an improvement over the prior art and in addition contains an advantage forming another object of this invention characterized by the simplicity of the apparatus, its few working parts, its economy of 25 operation, and the small amount of space required for it.

In the manufacture of paper and cardboard boxes, many thousands are generally run through 30 on a single order and any means which tends to expedite the formation of them and reduces the waste and cost without sacrificing quality and proper construction, is a material contribution and advance in the art.

40 Referring now to the drawing forming a part of this application and wherein like reference numerals indicate like parts:

Figure 1 is a front side view of my improved apparatus, certain parts being shown diagrammatically for clearness of illustration.

Figure 2 is an edge view of one size of die or template which is used in connection with my invention.

Figure 3 is an edge view of another size of die 50 or template.

Figure 4 is a perspective view of a paper or cardboard box such as my invention is used with.

The reference character 1 indicates a suitable support which may be fastened in any suitable 55 manner to a wall or the floor and upon which is

mounted in vertical position by any suitable bracket means a cylinder 2, communicating at its upper end through pipe 3, valve housing 4 and pipe 5, with a valve housing 6. A piston (not shown) is adapted to reciprocate within the cylinder 2 and has a stem 7 projecting out the lower end of the cylinder, such stem carrying a presser pad 8 of suitable size.

The lower end of the cylinder 2, below the piston in the cylinder, communicates through a pipe 9 with the valve housing 6. A valve control handle or lever 10 is provided for operating a valve in the valve casing 4. Also mounted upon the supporting panel 1 directly beneath the presser pad 8 is a solid block or anvil 11 upon which is adapted to be removably secured as by the screw 12 a die or template 13 which, as shown in Figures 2 and 3, may be of any desired size and shape depending upon the size and shape to be processed.

20 A suitable motor 14 drives a compressor 15 having connection through a pipe 16 with a tank 17 which also communicates through pipe 18 with the valve housing 6. A pipe 19 connects the tank 17 with a pressure gauge 20.

25 The pipe 21 connects the compressor 15 with a valve housing 22 within which is mounted a valve 23 which when open, establishes communication between the compressor 15 and the atmosphere.

30 The valve housing 6 is provided with a suitable valve arrangement (not shown) operable by a foot treadle 24 whereby the valve assembly within the housing 6 is controlled and operated by the foot.

35 In forming paper or cardboard boxes such as is shown at B in Figure 4, these are usually cut in bat blanks with sides 25, bottom 25, and ends 27. The ends 27 are provided as extensions of the box 26. The sides 25 also are provided with flap extensions 28 which are folded inside of the end members 27.

40 Both the sides and ends are usually provided with flaps 29 for turning down inside of the box for reinforcing the open side edges thereof.

45 When the blank is formed, it is folded to the position shown in Figure 4 with the flaps 28 inside the ends 27 and glue is applied to secure the flaps 28 to the ends 27 and also glue is applied to the underside of flaps 29 which overlie the flaps 28 on the inside of the box. When the glue is applied, a considerable amount of pressure is necessary to press these parts together to bring about a firm adhesion and at the same time to flatten and shape the ends of the box as they are 50 55

being secured. In carrying out this pressure applying operation, the end of the formed box, after the glue has been applied, is placed over the die or template 13 so as to underlie the presser pad 8. The presser pad 8 is then caused to descend under pressure and engage the end of the box placed on such die.

The operation of my apparatus is as follows: First the motor 14 is started as by means of an electric switch 38, and with the valve 23 closed, the air compressor 15 compresses air within the tank 17. In the normal position and with the foot treadle 24 in its normal raised position, the compressed air from the tank 16 passes through the valve box 8 and through pipe 9 into the lower end of the cylinder 2, thus normally holding the plunger or piston therein upwardly and maintaining the presser pad 8 in its raised position.

During the use of the machine the valve handle 18 is manipulated to open the valve in the housing 4. When the box end is placed over the die or template 13 in position for pressing, the operator presses the foot treadle 24 which operates the valve in housing 8 to exhaust the air from pipe 9 and to admit pressure from the tank 17 through pipe 5, valve housing 4 and pipe 3 to the upper end of the cylinder to above the piston. This forces the piston downwardly and causes the presser pad 8 to engage with the box end overlying the die 13. This condition prevails as long as the foot treadle 24 is depressed. As soon as pressure on the treadle is removed and it is permitted to raise to its normal position, the air is exhausted from the cylinder 2 above the piston through the valve housing 8 and pressure is again applied through pipe 9 to the underside of the piston forcing it upwardly to its normal position and raising the presser pad 8 from the box end and die.

The gauge 20 shows the operator the amount of air pressure available at all times.

The machine is provided with a set of dies 13 of any desired number, size, and shape. These can readily be substituted one for another by means of the holding screw 12 in the supporting block 11.

When the machine is not in use, the valve handle 18 should be turned to close the valve in housing 4 so as to prevent inadvertent admission of pressure to the upper end of the cylinder, as when changing the dies 13 or the like. This reduces danger of accidental depression of the presser pad 8.

Also when the machine is not in use the valve 23 should be open to the atmosphere to exhaust the air from the compressor 15 so that when the motor 14 is again started up there is no load against which it must start turning the compressor.

Of course, changes may be made in details of construction and arrangement of parts without departing from the spirit and scope of my invention. I do not limit myself, therefore, to the exact form herein shown and described other than by the appended claims.

I claim:

1. A box forming machine comprising a fixed support for a box to be formed, a template removably secured to said support, a reciprocable

plunger having a presser pad adapted to engage a box on said template, manually controlled, fluid actuated means for forcing said plunger and presser pad into engagement with said template, said means comprising a cylinder within which said plunger operates as a piston, means for admitting fluid selectively to either side of said piston in said cylinder, and a source of supply for said fluid.

2. A box forming machine comprising a fixed support for a box to be formed, a cylinder, a piston reciprocable therein, a plunger carried by said piston outside said cylinder and adapted to press against a box on said support, a source of air pressure, means for admitting air pressure from said source selectively to either side of said piston to force said plunger into or out of engagement with said support, and manually controlled means for actuating said air admitting means.

3. A box forming machine comprising a fixed support for a box to be formed, a cylinder, a piston reciprocable therein, a plunger carried by said piston outside said cylinder and adapted to press against a box on said support, a source of air pressure, means for admitting air pressure from said source selectively to either side of said piston to force said plunger into or out of engagement with said support, and manually controlled means for actuating said air admitting means, said air being normally admitted to said cylinder to move said piston and plunger away from said support.

4. A box forming machine comprising a fixed support for a box to be formed, a cylinder, a piston reciprocable therein, a plunger carried by said piston outside said cylinder and adapted to press against a box on said support, a source of air pressure, means for admitting air pressure from said source selectively to either side of said piston to force said plunger into or out of engagement with said support, manually controlled means for actuating said air admitting means, said air being normally admitted to said cylinder to move said piston and plunger away from said support, an air compressor communicating with said source of air pressure supply, and a relief valve and vent communicating with said compressor.

5. A box forming machine comprising a fixed support for a box to be formed, a cylinder, a piston reciprocable therein, a plunger carried by said piston outside said cylinder and adapted to press against a box on said support, a source of air pressure, means for admitting air pressure from said source selectively to either side of said piston to force said plunger into or out of engagement with said support, manually controlled means for actuating said air admitting means, said air being normally admitted to said cylinder to move said piston and plunger away from said support, an air compressor communicating with said source of air pressure supply, a relief valve and vent communicating with said compressor, and a safety valve in the air line from said source to the side of said piston which receives the air for forcing said plunger into support engagement, said valve being operable independently of said actuating means.

WALTER E. POPE.
